PATRICK J. CLARK, OF WEST MERIDEN, CONNECTICUT.

Design No. 4,678, dated February 28, 1871.

DESIGN FOR A DRAWER-PULL.

The Schedule referred to in these Letters Patent and making part of the same.

To all whom it may concern:

Be it known that I, PATRICK J. CLARK, of West Meriden, in the county of New Haven and State of Connecticut, have invented a new and original Design for a Drawer-Pull; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

I claim as my invention—

The design for a drawer-pull, as shown in the drawing.

PATRICK J. CLARK.
